W. Waller,

Pessary.

No 14,993.

Patented June 3, 1856.

UNITED STATES PATENT OFFICE.

WM. ALLEY, OF COLUMBUS, GEORGIA.

UTERINE SUPPORTER.

Specification of Letters Patent No. 14,993, dated June 3, 1856.

To all whom it may concern:

Be it known that I, WILLIAM ALLEY, of Columbus, in the county of Muscogee, in the State of Georgia, have invented and dis-
5 covered an Improved Pessary; and I do hereby declare that the following is full and exact description thereof.

The nature of my invention consists in the addition of circular wings, springs and
10 hinges to the common or ordinary pessary now in use, and worn by females to prevent the falling of the womb.

To enable others skilled in the art to make and use my invention I will proceed
15 to describe its construction and operation.

I take the ordinary pessary now in use and on the inside edge of the rim on the convex side I attach opposite each other a perpendicular wing—which are connected
20 at their base with hinges—and on the inside of each wing and attached to the pessary I place two perpendicular springs of any given strength, which may please the wearer of the instrument.

25 This instrument is better adapted than

any other to be worn by females who are suffering from the falling of the womb, from the fact that the wings with the springs attached prevent the instrument from getting misplaced; further, that is so 30 constructed as to apply itself to the vagina, applying itself to the curve in the acrum. Its springs also gently pressing against the wings assist greatly in its adaptation to the parts, producing ease and comfort to 35 the wearer and preventing any irritation whatever. The neck of the womb adjusting itself in the concave side of the pessary, in the center of which there is an orifice, to pass off the menstrual fluid. 40

What I claim as my invention and discovery and desire to secure by Letters Patent is—

The circular wings perpendicular springs and the hinges to the wings.

WILLIAM ALLEY.

Attest:

CHAS. P. LEVY,
SYLVESTER PECK.
